UNITED STATES PATENT OFFICE

ALEXANDER X. KENNEDY, OF TYRONE, PENNSYLVANIA

MEANS FOR FASTENING ROLLS TO SHAFTS

Application filed May 7, 1928. Serial No. 275,948.

This invention relates to new and useful improvements in means for fastening rolls to shafts, such as core shells for rolls of web material upon shafts to facilitate winding or 5 unwinding of the web material, and more particularly to chucks for insertion in the ends of cores for paper rolls for securing the same to shafts.

Such devices, as are in general use for this 10 purpose, consist generally of tapered bodies adapted to be forced into the ends of the web core, but which have proven unsuitable for the reason that the entire weight of the web material on these cores is imposed at the ends 15 of the core and upon the tapered bodies inserted in these ends, which causes the ends of the core to bell or cup and frequently split, thereby permitting play between the ends of the core and the tapered bodies of the chucks, 20 which causes the roll of web material to bob and weave back and forth during its rotation with detrimental effects upon the web material. It is, therefore, an important object of this invention to provide a device 25 which will obviate this objection and one which may be easily and quickly adjusted so that it will adapt itself to the irregularities of surface within the core, so as to obtain a firm driving grip upon the core at 30 several points around its inner circumference without causing the ends of the core to become cupped or split.

Another important object of the invention, resides in the construction and arrangement 35 of parts of the chuck whereby it may be constructed of minimum weight and size while still possessing the essential strength.

A still further object of the invention resides in the provision of a chuck of the above 40 character in which the parts are interchangeable which not only makes for a reduction in the cost of manufacture, but facilitates the repair or replacement of any of its parts.

Other objects and advantages of the invention will become apparent during the course of the following description.

In the accompanying drawings forming a part of the description, and wherein like numerals are employed to designate like parts 50 throughout the several views:

Figure 1 is a perspective exploded view of the chuck, with parts shown in section.

Figure 2 is a side elevation of the chucks showing them applied to a core and shaft.

Figure 3 is a longitudinal section of one 55 of the chucks showing it in position upon the shaft, and within one end of a core.

Figure 4 is a transverse section of the same taken on the line 4-4 of Figure 3, and

Figure 5 is a fragmentary longitudinal 60 section of one end of one chuck illustrating the manner of keying the same to a core.

Referring now, more particularly to the drawings, wherein, for the purpose of illustration, I have shown one example of my improved chuck, the numeral 5 designates an element which is adapted to be mounted upon and fixed to a shaft 6 for rotation therewith, and in the present instance is illustrated in the form of a cylindrical iron core shell, such 65 as is usually employed for mounting rolls of web material to be wound or unwound therefrom.

The chucks comprising my present invention are designated in general by the numeral 75 7, and one of these chucks is adapted to be inserted into each end of the core 5 for abutment with the ends thereof and secured to the shaft 6 for rotation therewith, so as to impart rotary movement to the core. As 80 the chucks for opposite ends of the core, are of the same construction, a description of one will suffice for both.

These chucks each comprise a cylindrical tubular body portion 8, which possesses an 85 outside diameter closely approximating the inside diameter of the core 5, so that it may be readily slipped into the end of the same, and an inside diameter to snugly and slidably fit upon the shaft 6. This shaft 6 is equipped 90 with a key 9, and the body of the chuck with a longitudinally extending key seat 10 for the reception of the key for fixing the body upon the shaft while permitting it to slide longitudinally thereof. This key seat 95 10 of the body, obviously extends throughout the entire length thereof to permit the chuck being moved longitudinally of the shaft and into the end of the core 5.

Adjacent the outer end of the body por- 100

tion of the chuck, an integral annular flange 11 of substantial width is formed on the exterior of the body to form an abutment with the end of the core, as clearly shown in Figs. 2 and 3, and serves to limit the inward movement of the chuck within the core. The inner face of the flange 11 is provided with a radially arranged slot or recess 12' for the reception of a dowel or key 12, which projects beyond the periphery of the body 8 to enter a kerf or slot provided in the end of the core 5 to establish a positive driving connection between the chuck and core. An opening 13' smaller than the recess 12' extends from the inner portion of the latter to the outer face of the flange 11 and is adapted to be aligned with an opening 14' extending entirely through an adjusting collar 23 in order that a suitable tool or instrument may be moved into aligned openings 13' and 14' to force the key 12 out of its recess 12' when the chuck is unassociated with a core, should replacement of the key be necessary.

Beyond and outwardly of the annular flange 11, the body of the chuck is reduced and extended, as at 13 for a purpose which will be later described.

The exterior surface of the main body portion 8 is provided with a plurality of inwardly tapered longitudinally extending wedge grooves 14 arranged equidistantly around the circumference and spaced apart about 120° in order that three of such grooves will be provided, although it is, of course, understood that a smaller or larger number of grooves may be formed without departing from the scope of this invention. The deepest part of each groove 14 is disposed adjacent the inner end of the body portion while the shallower portions are disposed adjacent the outer part or annular flange 11, and are arranged in alignment with dove-tailed grooves 15 extending longitudinally throughout the reduced portion 13 of the body and into the main body portion 8 to a depth greater than the outer ends of the tapered grooves 14 to provide ledges or shoulders 16 at the juncture of the grooves 14 and 15. The grooves 15 are, of course parallel with the axis of the chuck, and do not taper as do the grooves 14. The latter grooves are likewise of dove-tailed shape, so as to provide overhanging side edges to prevent accidental displacement of wedges 17, which are adapted to slide longitudinally therein, while moving radially of the chuck, due to the inclined bottoms of the grooves 14.

These wedges 17 are shaped with edges to fit the dove-tailed grooves 14, and are provided with concave inner surfaces and convex outer surfaces to conform to the bottoms of the grooves 14 and to the exterior surface of the main body portion of the chuck. In Fig. 3, it will be observed that the inner smaller ends of the wedges project beyond the

shoulders 16, and are there provided, each with a rectangular recess or opening 18, adapted to loosely receive the angular end or projection 19 of a knuckle or segment 20. These segments are provided with tapered edges to be slidably mounted in each of the dove-tailed grooves 15 for cooperation with its respective wedge 17, and, of course, like the wedges 17, are provided with inner concave surfaces to fit the bottom of its respective groove 15, and outer convex surfaces, which project beyond the exterior surface of the reduced body portion 13. The exterior surfaces of these segments 20, are all provided with corresponding screw threaded portions 21 for a purpose which will be presently described. The connection of the segment knuckles 20, with the wedges 17, provides in effect, an offset at the shoulder 16, which not only makes for the compactness of the chuck, but for the reduction in expenditure for replacement of the segments 20, should their threads become impaired in use. In view of the flexibility or loose and detachable connection between the segments 20 and the wedges, and the fact that these two parts are interchangeable with corresponding parts, enables a reduction in the expense in replacing or repairing these parts when they become unfit for use, since a segment may be replaced without necessitating the replacement of a good cooperating wedge 17, or vice versa.

Of course, the integral annular flange 11 of the chuck is provided with openings 20, directly above the grooves to provide space for the operation and movement of the outer smaller ends of the wedges 17, when they are actuated by the segments 20 to move them radially and outwardly of the chuck during their expanding movement. These wedges 17 will be hereinafter referred to as an expansive and contractile instrumentality mounted upon the body of the chuck. It is obvious that when the segments 20 are moved inwardly of the chuck that corresponding movement is imparted to the wedges 17, thereby effecting a contraction of the instrumentality, whereby the chuck may be readily inserted into the core 5.

The means for operating the expansive and contractile instrumentality consisting of the wedges 17, comprises an internally screw threaded collar 23 rotatably mounted upon the reduced extension 13 of the body to engage the threads 21 of the various segments for moving them together with the wedges 17 outwardly or inwardly of the chuck. Means are provided for rotatably interlocking this collar 23 to the flange 11 of the chuck, and consists of a plurality of V-shaped lugs 24 extending from the inner face of the collar 23, and are rotatably associated with an internal V-shaped annular groove 25, provided in the flange 11. As clearly seen in Figs. 1 and 3,

the inner arcuate surfaces of these lugs 24 are provided with continuations on the interior thread of the collar, which is of the same pitch as the threads 21 provided on the segments 20.

In order to assemble the adjusting collar 23 with the flange 11 and to dispose the lugs 24 within the internal groove 25 of the flange, the latter is equipped with a plurality of radially disposed dove-tailed ways or slots 26, corresponding in number to the number of lugs 24 provided upon the collar, and of a width to admit these lugs upon movement of the collar toward the flange 11. After the lugs 24 have been inserted through the ways 26, the adjusting collar is given a partial turn on the axis of the chuck, so as to cause these lugs 24 to pass into the annular groove 25 and interlock the collar with the flange. Thereafter, arcuate dove-tailed filler blocks 27 are fitted into the ways 26 to completely close the same, and screws 28 are screwed lengthwise into the joint between these blocks and the flange 11 to securely maintain them in place and against accidental radial displacement. The inner surface of each filler block 27 is equipped with an arcuate V-shaped groove 28, so that when these blocks are inserted into the ways 26, the grooves 28 form a continuation of the internal groove 25, whereby the collar 23 may be turned through a complete revolution without danger of its axial displacement. Radial pin wrench openings 29 are provided in the exterior surface of the adjusting collar 23, whereby a wrench or other instrument may be inserted to facilitate rotation of the collar in either direction.

In order to prevent the chuck from slipping longitudinally upon the shaft 6 and to maintain the flange 11 in engagement with the end of the core 5, means are provided in the chuck for engaging the key 9 of the shaft 6. This means consists broadly of a machine screw 30, threaded radially through the flange 11 for engaging the outer surface of the key 10. Similar screws have been provided heretofore, but which have been threaded directly into the chuck body with the result that when the threads become worn or damaged, it is necessary to retap the threaded opening and provide a slightly larger screw. As periodic re-tappings are made, the screw opening becomes so large as to render the chuck unfit for further use; the improvements which I will now describe are designed to eliminate this shortcoming of previous chucks.

The flange 11 is provided with a radially extending opening 31, which extends entirely through the inner surface of the chuck, and a removable interiorly threaded screw bushing 32 is fitted into the opening 31 to receive the machine screw 30, which is adapted to bear against the key 9. In order to securely

fasten this bushing within the opening and at the same time enable its removal for replacement when necessary, the outer end of the bushing is equipped with a pair of diametrically and outwardly extending wings 70 33, which are adapted to pass through the key-hole outer end of the opening 31 formed by providing the outer end of the opening with diametrically disposed recesses 34, after which the bushing is given a half turn to dispose the wings 33 within diametrically disposed undercut portions 35 of the opening. A pair of filler blocks 36 shown in Figs. 2 and 4, are then inserted into the recess 34 of the flange to completely fill the same, and are 80 removably secured therein by screws 37 passing through the filler blocks and into threaded openings in the bottoms of the recess 34. The screw 30 may then be driven home to bind upon the key 9, and thereby secure the bushing against longitudinal sliding movement upon the shaft 6.

In order to mount the chuck upon a shaft and within the end of the core 5, the adjusting collar 23 is rotated in a direction to cause the wedges 17 to move toward the inner end of the body portion 8, thereby contracting the expansive and contractile instrumentalities, in order that the chuck, after having been slid along the shaft may have its body portion 8 slipped into the end of the core 5 with the dowel 12 fitting the kerf in the end of the core, and the flange 11 abutting the end of the core 5. The machine screw 30 is then driven home upon the key 9 to prevent accidental axial movement along the shaft 6. The adjusting collar 23 is then turned in the opposite direction with its lugs 24 moving through the annular groove 25 in the flange, so as to cause the threaded segments 20 to move outwardly of the chuck and end of the core drawing with them the wedges 17, thereby causing the latter to move radially and expand into firm bearing contact with the inner surface of the core, at which time the 100 chuck is then securely locked upon the shaft, and is securely and firmly engaged with the inner surface of the core, so as to cause its rotation with the chuck and shaft to either wind upon or unwind web material from the 110 core.

Of course, it will be obvious that my improved chuck is not limited to its use in connection with cores for web material, but is of general application as a means of coupling 120 one member to another.

Various changes in the size, shape and arrangement of the various parts may be resorted to without departing from the spirit of the invention or the scope of the appended 125 claims.

What I claim is:

1. A chuck comprising a body adapted to be mounted upon a shaft and inserted into a cylinder, said body having an integral flange 130

for abutment with the end of said cylinder, a plurality of movable wedges mounted on the exterior of said body, and an adjusting collar rotatably mounted upon said body and being interconnected to said flange for operating said wedges.

2. A chuck comprising a body, said body having an integral flange, said body having a tapered portion the larger part of which is disposed nearer said flange than the smaller part thereof, a wedge member slidably mounted upon the exterior of said tapered portion and provided with offset operating means adjacent the larger part of said tapered portion, and an adjusting member rotatably mounted upon said body and being operably connected to said offset operating means whereby rotation of said member in one direction will cause movement of said wedge member outwardly of said body and toward the larger part of said tapered portion.

3. A chuck comprising a body, said body having an integral flange, said flange being provided with an internal groove, an expansive and contractile instrumentality carried by said body, an adjusting collar rotatably mounted upon said body for actuating said instrumentality, and said collar having means operating in said internal groove for rotatably interlocking said collar and flange.

4. A chuck comprising a body, said body having an integral flange, said flange being provided with an internal groove, an expansive and contractile instrumentality carried by said body, an adjusting collar rotatably mounted upon said body for actuating said instrumentality, and said collar having a plurality of lugs arranged for rotation in said internal groove for rotatably interlocking said collar and flange.

5. A chuck comprising a body, said body having an integral flange, said flange being provided with an internal groove and ways leading into said groove, an expansive and contractile instrumentality carried by said body, an adjusting collar rotatably mounted upon said body for actuating said instrumentality, and said collar having a plurality of lugs for passage through said ways to operate in said internal groove, and means for closing said ways to rotatably interlock said collar and flange.

6. A chuck comprising a body, said body having an integral flange, said flange being provided with an internal annular V-shaped groove, an expansive and contractile instrumentality carried by said body, an adjusting collar rotatably mounted upon said body for actuating said instrumentality, and said collar having a plurality of V-shaped lugs arranged for rotation in said internal groove for rotatably interlocking said collar and flange.

65 7. A chuck comprising a body, said body

having an integral flange, said flange being provided with an internal groove and dove-tailed ways leading into said groove, an expansive and contractile instrumentality carried by said body, an adjusting collar rotatably mounted upon said body for actuating said instrumentality, said collar having a plurality of lugs for passage through said ways to operate in said internal groove, and removable dove-tailed filler blocks closing said ways to retain said lugs within said groove.

8. A chuck comprising a body, said body having an integral flange, said flange being provided with an internal annular groove and ways leading into said groove, an expansive and contractile instrumentality carried by said body, an adjusting collar rotatably mounted upon said body for actuating said instrumentality, said collar having a plurality of lugs for passage through said ways to operate in said internal groove, and removable filler blocks closing said ways and having grooves to align with and form continuations of said internal groove.

9. A chuck comprising a body adapted to be mounted upon a shaft and frictionally engaged with a cylinder, an expansive and contractile instrumentality carried by said body for engaging the inner walls of said cylinder, a removable screw mounting mounted in said body, and a screw associated with said mounting for keying said body to said shaft.

10. A chuck comprising a body adapted to be mounted upon a shaft and inserted into a cylinder, said body having stationary means for abutment with the end of said cylinder, an expansive and contractile instrumentality carried by said body for frictionally engaging said cylinder, said body having an opening with interlocking means, a removable bushing mounted in said opening, means cooperating with said interlocking means to releasably retain said bushing in said opening, and a screw mounted in said bushing for fixing said body upon said shaft.

11. A chuck comprising a body adapted to be mounted upon a shaft and inserted into a cylinder, said body having stationary means for abutment with the end of said cylinder, an expansive and contractile instrumentality carried by said body for frictionally engaging said cylinder, said body having an opening formed with a key-hole mouth, a removable bushing mounted in said opening and having a pair of interlocking wings for interlocking engagement with said key-hole mouth, and a screw mounted in said bushing for securing said body upon said shaft.

12. A chuck comprising a body, a plurality of longitudinally movable wedges slidably mounted upon said body, an adjusting member rotatably mounted upon said body, and interchangeable means connected to said wedges and operatively connected to said ad-

justing member, said interchangeable means having threads by which the wedges are moved.

13. A chuck comprising a body, a plurality of wedges slidably mounted upon said body and provided with recesses, an adjusting member rotatably mounted upon said body for actuating said wedges, and interchangeable members having projections fitting said recesses and operatively connected to said member, said interchangeable means having threads by which the wedges are moved.

14. A chuck comprising a body, a plurality of wedges slidably mounted upon said body and provided with recesses, an internally threaded collar rotatably mounted upon said body, interchangeable threaded segments slidably mounted upon said body for cooperation with the threads of said collar, and said interchangeable segments having angularly disposed ends fitting said recesses of said wedges.

15. A chuck comprising a body, said body having a groove with an inclined bottom, a second groove in alignment therewith and forming a shoulder therewith, a wedge member slidably mounted in said first groove with its smaller end projecting over said shoulder and provided with a recess, and means for sliding said wedge including a member slidably mounted in said second groove and having a projection entering said recess.

16. A chuck comprising a cylindrical body portion provided with a longitudinally extending groove, said body having an integral flange provided with an opening in alignment with said groove, an adjusting collar rotatably mounted upon said body, and a wedge member slidably mounted in said groove and extending through the opening in said flange to be operatively connected to said collar.

17. A chuck comprising a body, a plurality of wedges slidably mounted thereon, an internally threaded collar rotatably mounted upon said body, and slidably threaded segments cooperating with said collar and having loose connections with said wedges, the threads of said segments cooperating with the collar to move said wedges.

50 In testimony whereof I have hereunto set my hand.

ALEXANDER X. KENNEDY.
